FRIEDRICH LUTZ, OF STUTTGART, GERMANY, ASSIGNOR TO UNION SPECIAL MASCHINENFABRIK, G. M. B. H., OF STUTTGART, GERMANY

PRESSER FOOT AND CHAIN CUTTER FOR SEWING MACHINES

Application filed October 27, 1928, Serial No. 315,464, and in Germany June 29, 1928.

The invention relates to new and useful improvements in a presser foot for sewing machines, and a chain cutter which is associated therewith.

- 5 An object of the invention is to provide a presser foot with means cooperating with the feed and the throat plate for feeding and holding the enchainied thread loops between the stitched articles.
- 10 A further object of the invention is to provide a presser foot and chain cutter of the above type wherein the presser foot is so constructed as to control and guide the chain and insure the feeding of the chain into the
- 15 chain cutter.

A still further object of the invention is to provide a presser foot and chain cutter of the above type wherein the enchainied loops are gripped and held while the same are being severed.

In the drawings which show by way of illustration one embodiment of the invention:

Figure 1 is a view partly in section and partly in side elevation showing a portion of the machine embodying the improvements;

Fig. 2 is a view partly in front elevation and partly in vertical section of the parts shown in Fig. 1;

Fig. 3 is a view partly in section and partly in plan of the parts shown in Fig. 1;

Fig. 4 is a view showing more or less diagrammatically partly in plan and partly in section the arrangement of the throat plate, the presser foot members, and the cutter;

Fig. 5 is a plan view of the throat plate showing the feed sections and also showing the enchainied loops as positioned for severing;

Fig. 6 is a vertical view in section through the center of the presser foot showing the auxiliary section controlling the enchainied thread loops, the feed section cooperating therewith, the throat plate and the severing devices at the time when the chain is being fed;

Fig. 7 is a view similar to Fig. 6 but showing the parts positioned so that the chain is clamped and is being severed by the cutting devices;

Fig. 8 is a view partly in section and part-

ly in side elevation showing the position of the parts as a section of fabric enters beneath the front end of the foot.

The invention is directed broadly to a presser foot and chain cutter for sewing machines. The presser foot is constructed preferably with two sections which are independently mounted. These presser foot sections cooperate with the feed dog in the feeding of the material to the stitching mechanism. Located between the two sections is an auxiliary presser foot which is mounted on one of the presser foot sections or on the machine frame so as to move independently of the foot sections. A spring normally depresses the auxiliary section and yieldingly holds the auxiliary section against the material or against the enchainied thread loops passing beneath the same. Cooperating with this yielding section is a section of the feed dog which feeds the enchainied thread loops when there is no material beneath the auxiliary foot section. The throat plate and the auxiliary section are provided with toothed portions, which firmly grip the enchainied thread loops and hold the same when the feed dog is on its idle movement. Associated with the presser foot is a chain cutter, which includes a stationary blade and a movable cutter blade which may be operated for severing the enchainied thread loops held clamped between the auxiliary presser foot and the throat plate.

Referring more in detail to the drawings, the invention is shown as applied to a sewing machine which includes a throat plate 1 having feed slots 2, 2 therethrough through which the sections 3, 3 of the feed dog operate. Centrally of the throat plate is an opening 4 for the needle 5 of the machine. The needle 5 is carried by a needle bar 6, which reciprocates in the usual manner in an overhanging arm, a portion of which is indicated at 7 in the drawings.

The throat plate is provided with a slot 8 in rear of the needle opening in which a section 9 of the feed dog operates. At the rear end of the slot 8 there is a bridged portion 10 provided with teeth on its upper face. The feed sections are all provided with teeth on

their upper face and the middle section 9 of the feed dog is rounded off at 11 so as to avoid cutting the chain. The material is held on the work support by two presser feet, one of which is indicated at 12 and the other at 13. 5 The presser foot 12 is carried by a presser bar 14, and the presser foot 13 is carried by a presser bar 15. The presser foot 13 is pivotally secured to the presser bar by means of a pivot bolt 16. The presser foot 12 is pivotally secured to the presser bar 14 by a pivot bolt 17. This provides means whereby the sections of the presser foot can tilt on the presser bars when a section is laid underneath 10 the presser feet. The presser foot 13 is the main presser foot of the machine and has a portion which extends around in front of the needle. The two presser feet are spaced from each other in the region in rear of the needle 15 and this forms a guiding channel for the en- 20 chained thread loops causing said en- chained thread loops as they feed away from the stitching point to move directly toward the rear of the machine. Located in this channel between the two presser feet is an auxiliary 25 presser foot 18. The auxiliary presser foot 18 is rigidly connected to a supporting stand- 30 ard 19, which moves freely in a sleeve 20 car- ried preferably by the presser bar 15. Located within this sleeve is a spring 21 which 35 normally presses the auxiliary presser foot downward toward the throat plate to yield- ily hold said foot against the fabric or en- chained thread loops. This auxiliary section of the presser foot is provided with a toothed portion 22.

Associated with the presser foot is a chain cutter, which includes a stationary cutting blade 23 supported in any suitable way, and 40 a movable cutting blade 24. The movable blade is mounted on a lever 25, pivoted at 26 to the bracket 27, which is secured by suitable screws 28, 28 to the presser bar 15. The sleeve 20 is also mounted on this bracket 27. 45 This lever 25 may be operated in any desired way, but is preferably actuated by article controlled means for the severing of the en- chained thread loops.

When a fabric to be stitched is passing beneath the presser feet both the presser feet and the auxiliary presser foot will be resting on top of the fabric and cooperate with the feeding sections of the feed dog to feed the material. After an article is stitched and passes 55 from beneath the presser feet a series of en- chained thread loops may be formed. The auxiliary section of the presser foot will en- gage the en- chained thread loops and cooperate with the central section of the feed dog 60 to feed said en- chained thread loops. The en- chained thread loops will lie in the channel between the two presser feet, and this will guide the en- chained thread loops so as to direct them into the severing devices. When 65 the auxiliary presser foot is pressing the en-

chained thread loops against the throat plate, the toothed section on the auxiliary foot and the toothed section on the throat plate will firmly grip and hold the en- chained thread loops. The cutting devices are immediately 70 in rear of the auxiliary section and the bridg- 75 ing portion of the throat plate which carries this toothed portion. Therefore, the cutter when operated will sever the en- chained thread loops close to the point where they are gripped and this will hold the en- chained thread loops and insure the proper severing of the same. When a fabric section is started beneath the presser feet the presser feet will be tilted as shown in Fig. 8 of the drawings. 80 At this time however the auxiliary presser foot will move down beneath the lower face of the presser feet and will engage the en- chained thread loops and continue to feed the en- chained thread loops until the fabric section reaches the needle so that the threads are anchored in the material, after which of course the en- chained thread loops will be fed with the material.

The purpose of the improved presser foot 90 is to guide and feed the en- chained thread loops between stitched articles, and to hold said en- chained thread loops relative to the severing devices so that the en- chained thread loops may be severed at will. The severing devices are located very near to the needle 95 so that after the en- chained thread loops are severed there is a very short length of en- chained thread loops. While the fabric section is passing beneath the foot this auxiliary 100 section of the presser feet will control and feed the en- chained thread loops and prevent any skipping of stitches until the fabric reaches the needle so that the en- chained thread loops are anchored therein.

It is obvious that minor changes in the details of construction may be made without departing from the spirit of the invention as set forth in the appended claims.

Having fully described my invention, what I claim as new and desire to secure by Letters Patent, is:—

1. The combination of a presser foot having fabric engaging portions and a needle opening, said fabric engaging portions being spaced from each other in rear of the needle opening, an independently yielding auxiliary fabric and chain engaging portion located in said space, and a chain severing device located directly at the rear of said yielding section for severing the en- chained thread loops.

2. The combination of a presser foot having fabric engaging portions and a needle opening, said fabric engaging portions being spaced from each other in rear of the needle opening, an independently yielding auxiliary fabric and chain engaging portion located in said space, a feed dog having feed- 125 ing sections cooperating with the fabric en- 130

gaging portions of the presser foot and having an independent feeding section cooperating with said auxiliary fabric engaging portion, and a chain severing device located directly at the rear of said yielding section for severing the enchain'd thread loops.

3. The combination of a presser foot having independently mounted fabric engaging portions one of which is provided with a 10 needle opening, said fabric engaging portions being spaced from each other in the region in rear of the needle for forming a channel to guide the enchain'd thread loops during chaining between stitched articles, an 15 independently yielding auxiliary section located in said space for engaging said enchain'd thread loops during chaining, a feed dog having feeding sections cooperating with the fabric engaging portions of the presser 20 foot and having a feeding section cooperating with said auxiliary fabric engaging portion for feeding the enchain'd thread loops, and a chain severing device disposed at the rear end of said auxiliary fabric engaging 25 portion.

4. The combination of a presser foot having independently mounted fabric engaging portions one of which is provided with a needle opening, said fabric engaging portions being spaced from each other in the region in rear of the needle for forming a channel to guide the enchain'd thread loops during chaining between stitched articles, an independently yielding auxiliary section 30 located in said space for engaging said enchain'd thread loops during chaining, a feed dog having feeding sections cooperating with the fabric engaging portions of the presser foot and having a feeding section cooperating 35 with said auxiliary fabric engaging portion for feeding the enchain'd thread loops, a throat plate having a bridging portion in rear of said feeding section which cooperates with the auxiliary fabric engaging portion, 40 said bridging portion and said auxiliary fabric engaging portion having toothed cooperating surfaces for gripping the enchain'd thread loops, and a severing device located directly in rear of said bridging portion for 45 severing the enchain'd thread loop while gripped between said throat plate and said auxiliary fabric engaging section.

5. The combination of a presser foot having fabric engaging portions pivotally supported so as to tilt in passing onto fabric sections, one of said sections having a needle opening therethrough, said sections being spaced in rear of the needle opening, an auxiliary fabric engaging portion located in said 55 space, means for supporting the same whereby it may yieldingly move vertically independently of the presser foot fabric engaging portions, a throat plate having feed slots and a bridging portion directly beneath the rear 60 end of said auxiliary fabric engaging por-

tion, a feed dog having feeding sections cooperating with the presser foot and the auxiliary section, a chain severing device including a lower stationary plate and an upper movable blade operating in a plane at right angles to the line of feed for severing the enchain'd thread loops, said severing device being located directly in rear of said auxiliary section. 70

6. The combination of a presser foot having fabric engaging portions pivotally supported so as to tilt in passing onto fabric sections, one of said sections having a needle opening therethrough, said sections being spaced in rear of the needle opening, an auxiliary fabric engaging portion located in said space, means for supporting the same whereby it may yieldingly move vertically independently of the presser foot fabric engaging portions, a throat plate having feed slots and a bridging portion directly beneath the rear end of said auxiliary fabric engaging portion, a feed dog having feeding sections cooperating with the presser foot and the auxiliary section, said auxiliary section and said 80 bridging portion having teeth for engaging and firmly clamping the enchain'd thread loops for holding the same while they are being severed, a chain severing device including a lower stationary blade and an upper movable blade operating in a plane at right angles to the line of feed for severing the enchain'd thread loops, said severing devices being located directly in rear of said auxiliary section. 85

In testimony whereof, I affix my signature.
